BOWLING GAME TABLE

Edward J. Collins, Los Angeles, Calif., assignor
to United States Woodcraft Corporation, Redondo Beach, Calif., a corporation of California

Application April 26, 1949, Serial No. 2,276

Term of patent 3½ years

(Cl. D34—3)

To all whom it may concern:

Be it known that I, Edward J. Collins, a citizen of the United States and resident of the city of Los Angeles, county of Los Angeles, State of California, have invented a new, original, and ornamental Design for a Bowling Game Table, of which the following is a specification, reference being had to the accompanying drawing, forming a part hereof, in which:

Fig. 1 is a top plan view of the bowling game table, showing my new design;

Fig. 2 is a side elevational view thereof;

Fig. 3 is a bottom plan view thereof;

Fig. 4 is a front elevational view thereof;

Fig. 5 is a fragmentary sectional view thereof, to an enlarged scale, taken on line 5—5 of Fig. 2; and

Fig. 6 is a fragmentary sectional view taken on line 6—6 of Fig. 1.

I claim:

The ornamental design for a bowling game table, substantially as shown.

EDWARD J. COLLINS.
